UNITED STATES PATENT OFFICE

129,713

DESIGN FOR A COMBINED STUD BUTTON AND PICTURE FRAME OR SIMILAR ARTI- CLE

Morris Shuwarger, Los Angeles, Calif.

Application July 12, 1941, Serial No. 102,089

Term of patent 3½ years

To whom it may concern:

Be it known that I, Morris Shuwarger, a citizen of the United States, residing in the city and county of Los Angeles, State of California, have invented a new, original, and ornamental Design for a Stud Button and Picture Frame or Similar Article, of which the following is a specification, reference being had to the accompanying drawing, forming a part thereof, in which:

Fig. 1 is a side elevational view of a combined stud button and picture frame with the cover thereof in an open position, showing my new design; and

Fig. 2 is a top plan view of the present design with the cover closed, indicating the appearance thereof when the design is worn.

The present design is characterized by a substantially flat circular plate having a raised edge around the periphery thereof, said raised edge being embellished to simulate a wreath. A cover is hinged to the edge and sets into the recess formed thereby. Said cover comprises a rim with a lens held therein. A stud or clasp of conventional design is attached to the under side of the new design whereby the same may be attached to a garment.

I claim:

The ornamental design for a combined stud button and picture frame or similar article substantially as shown and described.

MORRIS SHUWARGER.
